UNITED STATES PATENT OFFICE.

JONATHAN E. PIERCE, OF DEMING'S BRIDGE, TEXAS.

STOCK-CAR.

SPECIFICATION forming part of Letters Patent No. 311,781, dated February 3, 1885.

Application filed October 1, 1884. (No model.)

To all whom it may concern:

Be it known that I, JONATHAN E. PIERCE, a citizen of the United States, residing at Deming's Bridge, in the county of Matagorda 5 and State of Texas, have invented certain new and useful Improvements in Stock-Cars, of which the following is a description.

This invention relates to that class of devices used for shipping stock, such as live cattle; and it has for its object to guard the cattle from such injury as is likely to occur to a car full of cattle by the sudden starting or stopping of the car; to furnish means for guiding the cattle into the proper compartment of 15 the car, and to furnish means for working the device by a train-hand on top of the car.

To this end my invention consists in the construction and combination of certain parts of a stock-car, hereinafter described and claimed, 20 reference being had to the accompanying drawings, in which—

Figure 1 is a side elevation of a stock-car, showing parts of my invention. Fig. 2 is a plan view of a portion of the car, the top being removed. Fig. 3 is a transverse vertical section of a portion of a car, showing my central gate free to turn; and Fig. 4 is a transverse vertical section showing the gate with its bars extended to lock it.

30 A represents the body of the car, which may be of any usual construction suitable to carry stock.

B is the usual sliding car-door, provided with upright slats, two of which, C C, are separated only sufficient to receive the gate-bolts D.

E represents my gate provided with a central vertical shaft, F, which is journaled in the top and bottom of the car to support the 40 gate. This shaft F is central in the gate, and its bearings are in the center of the car width-wise, and opposite to the centers of the side doors, B.

G is a segment of a toothed wheel secured 45 to the gate near its top concentric with the shaft F.

H is a screw or worm engaging the teeth of segment G to turn the gate.

I is the worm-shaft extending to the outside 50 of the car, where it is provided with a hand-wheel, J, by which the worm, and thereby the gate, may be turned either by a train-hand on

top of the car or by a person beside the car. The object of turning the handle J is to swing the gate diagonally either way across the car 55 to the sides of the doors, as shown in dotted lines, Fig. 2, so as to guide the cattle, on entering the car, first to fill one compartment and then the other. To sustain this gate, which serves as a central partition to keep the 60 cattle from being thrown from end to end of the car by sudden starting and stopping, I have provided a series of bolts, D, to be slid out of both ends of the gate by the action of a rod, K, fitted to slide vertically in the shaft 65 F, and connected with the bolts D by brace-links L and joining-bars M. The vertical bars M and N are secured firmly to the bolts D, forming two separate frames, one each side of the central shaft. When the rod K is raised, 70 it draws these frames toward each other and retracts the bolts D. When the rod is lowered, it separates the frames and extends the bolts D beyond the side bars of the gate. When the gate is square across the car, these 75 bolts, projecting, will enter between the vertical bars C C of the doors and lock the gate, the doors being secured by hasps and staples in the usual manner. When the gate is set diagonal, it necessarily fails to fill the space 80 between the diagonally-opposite sides of the doors. Therefore I have provided a bolt to the space between each pair of cross-bars of the gate, to serve, when extended, as a bodily extension of the gate to fill the space. At the 85 same time I have provided apertures P at each side of the doors to receive the extended bolts D, to lock the gate in a diagonal position, and to sustain it against the pressure of the stock. The rod K is provided with a ring-handle, by which it may be operated by a train-hand on top of the car. Thus my device is convenient and effective in all the 90 points stated. The worm and gear enable an attendant to turn the gate, even though stock 95 may be pressing against it.

What I claim as my invention, and desire to secure by Letters Patent, is—

1. A gate vertically pivoted in a stock-car centrally opposite to the door thereof, and 100 means, substantially as described, for turning and securing the gate, as and for the purpose specified.

2. The combination, with a gate hung on

vertical pivots in the center of a car, of a gear-toothed segment secured to the gate concentric with its pivots, a worm engaging said gear, the shaft of the worm extending to the 5 side of the car, near the top thereof, and a hand-wheel on the shaft outside the car, as and for the purpose specified.

3. The combination, with a series of bolts fitted to a gate to be extended beyond its side, 10 and vertical bars joining the bolts, of a vertical rod fitted to slide in the gate, and brace-links connecting the vertical rod with the sliding bolts, substantially as shown and described.

4. The combination, with a gate vertically 15 pivoted in the center of a car opposite the centers of its side doors, and a series of bolts

fitted to slide in the gate and project beyond the sides thereof, of two vertical bars secured in each door at a distance apart to receive the bolts between them while the gate is square 20 across the car, and a series of apertures at each side of each door fitted to register with and receive the bolts when the gate is diagonal to the car, as shown and described.

The above specification of my invention 25 signed by me in the presence of two subscribing witnesses.

JONATHAN E. PIERCE.
